UNITED STATES PATENT OFFICE.

HENRY F. SCHMIDT, OF SWARTHMORE, PENNSYLVANIA, ASSIGNOR TO WESTINGHOUSE ELECTRIC AND MANUFACTURING COMPANY, A CORPORATION OF PENNSYLVANIA.

CIRCULATING PUMP.

1,419,692.

Specification of Letters Patent. Patented June 13, 1922.

Application filed April 16, 1920. Serial No. 374,374.

To all whom it may concern:

Be it known that I, HENRY F. SCHMIDT, a citizen of the United States, and a resident of Swarthmore, in the county of Delaware and State of Pennsylvania, have invented a new and useful Improvement in Circulating Pumps, of which the following is a specification.

This invention relates to systems for circulating or pumping fluids and particularly to cooling water circulating systems for condensers and it has for its object to produce a new and improved pumping or circulating system, together with a new and improved governing means therefor. A more specific object is to produce a water governor for pumping or circulating systems which is independent in operation of variations in pressure of the water passing through the system.

These and other objects are attained by means of apparatus embodying the features of my invention herein described and illustrated in the drawings accompanying and forming a part hereof.

In the accompanying drawing Fig. 1 is a diagrammatic view of a condenser installation embodying my invention, partially in section and partially in elevation, Fig. 2 is an enlarged sectional view of a portion of the apparatus shown in Fig. 1.

In the drawing I have illustrated a surface condenser 5 having a steam inlet port 6 at its top, a condensate outlet port 7 at its bottom, and an ejector 8 for withdrawing air and other non-condensable gases and vapors therefrom. At one end of the condenser I have shown an inlet water box 9 and at the other end an outlet water box 10. In operation, cooling water is delivered to the water box 9 and after passing through the cooling elements of the condenser, is discharged into the outlet water box 10, which may be connected with a suitable discharge conduit.

Connected with the water box 9 of the condenser 5, I have shown a circulating pump 11. As illustrated, the pump 11 is provided with an elbow shaped casing 12 having a converging diverging portion 13 and, at right angles thereto, a cylindrical inlet portion 14. In the throat of the converging diverging portion 13, I have shown a propeller 15, which is mounted on the end

of a rotatable shaft 16 axially aligned with the converging diverging portion 13 of the casing 12. As illustrated, the shaft 16 passes through the curved end of the casing 12 and is supported by a tube 17 which projects from the inner wall of the casing nearly to the throat of the converging diverging portion 13 of the casing.

As illustrated, the outer end of the shaft 16 is operatively connected to a turbine 18. The turbine illustrated is provided with an inlet port 19, and inlet valve 20, and an exhaust port 21. The valve 20, as shown, is connected to a diaphragm 22 by means of a suitable stem 23. Enclosing the stem 23, I have shown a compression spring 23^a, which tends to hold the valve 20 open. As illustrated, the diaphragm 22 is enclosed within a casing 24 which it divides into two chambers 25 and 26. In the arrangement illustrated, the chamber 25 is connected by means of a pipe 27 with the interior of the pump casing 12, and the chamber 26 is connected by means of a pipe 28 with an annular chamber 29 formed as shown in the tube 17 and surrounding the shaft 16.

Adapted to operate within the annular chamber 29, I have illustrated a pump runner or impeller 30, which is mounted on the shaft 16 and which receives water near its inner periphery through inlet ports 31 in the tube 17.

Cooling water for the condenser 5 is delivered to the pump 12 by means of a conduit 32, is entrained by the impeller 15 and is discharged through the diverging portion 90 of the converging diverging portion 13 of the casing 12 into the water box 9 of the condenser 5. In passing through this diverging passageway, a part of the velocity energy of the water is converted into pressure energy 95 in a manner well known to those skilled in the art. As illustrated, the water box 9 also diverges, thereby tending to further increase the pressure of the water as the water passes through it and at the same time allowing the 100 stream to spread out so that the water may enter all of the cooling elements of the condenser without any radical change in direction of flow.

The speed of the turbine 18 is regulated 105 by the positioning of the inlet valve 20 in response to unbalancing of the force of the spring 23^a and the differential pressure on

the diaphragm 22. When the turbine 18 is not running, the impeller 30 is stationary and consequently substantially the same pressure exists in both the chamber 25 and 5 the chamber 26. Under these conditions, the differential force acting on the diaphragm 22 is zero, and the spring 23^a moves the inlet valve 20 to its extreme open position.

When steam is delivered to the turbine 18 10 and it begins to speed up, the rotation of the impeller 30 creates an additional pressure in the annular chamber 29, and hence in the chamber 26, by reason of the centrifugal action of the impeller on the water delivered 15 to the annular chamber 29 through the ports 31. This pressure increases with the speed until it becomes high enough to overcome the force of the spring 23^a and to thereby partially close the inlet valve of the turbine 20 18. If for any reason, the load on the impeller 15 is increased to such an extent as to reduce the speed of the turbine 18, the pressure generated by the impeller 30 will become less, hence the differential pressure of 25 the fluid acting on the diaphragm 22 will be reduced and the spring 23^a will open the inlet valve 20 sufficiently to restore the speed to normal. Obviously, for each setting of the spring 23^a there is only one speed of 30 the pump which will produce equilibrium in the governor; consequently the speed may be varied by varying the compression of the spring 23^a.

Any variation in pressure of the water 35 entering the pump 11 will not affect the regulation of the turbine 18, for the reason that the increase will be transmitted equally to both sides of the diaphragm 22 and hence will be balanced. When used for marine 40 work this arrangement insures the proper governing of the turbine 18 irrespective of the varying draft of the vessel in which the system is installed.

While I have shown my invention in but 45 one form, it will be obvious to those skilled in the art that it is not so limited but is susceptible of various other changes and modifications, without departing from the spirit thereof, and I desire therefore, that only 50 such limitations shall be placed thereupon as are imposed by the prior art or as are specifically set forth in the appended claims.

What I claim is:—

1. In a circulating system, a pump, means 55 for actuating said pump, pressure responsive governing means therefor, means for varying the pressure on one side of the governing means in response to variations in speed of the pump actuating means, and 60 means for transmitting variations in pressure of the fluid passing through the pump to both sides of the governing means.

2. In a circulating system, a pump, means 65 for actuating the pump, pressure responsive governing means for controlling the speed

of the actuating means, means for subjecting one side of the pressure responsive means to the pressure of fluid in the circulating system, and means for subjecting the other side of the pressure responsive means 70 to fluid pressure which is a function of the speed of the pump.

3. In a condenser circulating system, a pump, a turbine for actuating said pump, pressure responsive means for governing 75 the speed of the turbine, an impeller receiving fluid from the circulating system for generating pressure to control the pressure responsive means, and means for balancing 80 variations in the pressure of the fluids in the circulating system.

4. In a circulating system, a pump, means for driving said pump, means for controlling the speed thereof comprising in part a chamber divided by a diaphragm, an impeller operated by the driving means, an annular chamber surrounding the impeller and having means for admitting fluid from the interior of the pump to the inner periphery of the impeller, means connecting the 90 outer part of the annular chamber with one side of the divided chamber, means connecting the other side of the divided chamber with the interior of the pump, and resilient means for opposing the differential pressure acting on the diaphragm.

5. In a circulating system, a pump, means for actuating said pump, pressure responsive governing means therefor, means for varying the pressure on one side of the governing means in response to variations in speed of the pump actuating means, and means for subjecting the other side of the governing means to the inlet pressure of 100 the system.

6. In a circulating system, a rotary pump, a turbine for actuating the pump, pressure responsive governing means for controlling the turbine speed, means including an impeller pump for varying the fluid pressure 110 on one side of the governing means in response to the turbine speed, and means for subjecting the other side of the governing means to the inlet pressure of the circulating system.

7. In a circulating system, a pump, means for actuating the pump, and means for controlling the actuating means comprising a diaphragm subjected on one side to the inlet fluid pressure of the system, and on 120 the other side to fluid pressure which is a function of the speed of the actuating means.

8. In a circulating system, a rotary pump, means for actuating the pump including a 125 turbine driving a shaft, an impeller pump on said shaft between the turbine and the rotary pump and means controlling the turbine comprising a diaphragm subjected on one side to the inlet fluid pressure of the 130

system and on the other side to the fluid pressure of the impeller pump.

9. In a circulating system, a pump, actuating means therefor, and control means for the actuating means including a diaphragm subjected on one side to a fluid pressure which varies with the speed of the actuating means and on the other side to the inlet fluid pressure of the system, and resilient means exerting mechanical pressure on the diaphragm in opposition to the first-named fluid pressure.

10. In a circulating system having a turbine driven rotary pump, a control means for the turbine comprising a throttle valve, a diaphragm actuating said valve, and means whereby the diaphragm is subjected on one side to fluid pressure which varies with the turbine speed and on the other side to the inlet fluid pressure of the system

and to a predetermined mechanical pressure.

11. In a condenser circulating system, a rotary pump, a condenser, and a diverging water box for the condenser in axial alignment with the pump, whereby the pump discharges axially into the condenser at a uniformly distributed pressure. 25

12. In a condenser circulating system, a condenser, a diverging water box therefor and a rotary pump having a diverging outlet discharging axially into the water box whereby water enters the condenser at a uniformly distributed pressure. 30

In testimony whereof, I have hereunto 35 subscribed my name this March 30, 1920.

HENRY F. SCHMIDT.
